L. KING.
MACHINE FOR MAKING CHAINS.

No. 43,778.

Patented Aug. 9, 1864.

UNITED STATES PATENT OFFICE.

L. KING, OF EAST CLEVELAND, OHIO.

IMPROVEMENT IN MACHINES FOR MAKING CHAINS.

Specification forming part of Letters Patent No. 43,778, dated August 9, 1864.

To all whom it may concern:

Be it known that I, L KING, of Cleveland, of Cuyahoga county, in the State of Ohio, have invented a new and useful Machine for Making Chains; and I do hereby declare that the following is a full, clear, and exact description thereof, reference being had to the accompanying drawings, making part of this specification, and to the letters of reference marked thereon, in which drawings—

Figure 1 is a top plan view of my machine; Fig. 2, a transverse vertical section of the same taken on the line $x-x$ of Fig. 1. Figs. 3, 4, and 5 are plan views of detached portions of the machine, and Fig. 6 represents the links of the chain in each of the various stages through which it passes in the process of being made.

Similar letters in each of the figures indicate corresponding parts of the machine.

The nature of my invention consists in constructing a machine by which the entire process of making a complete and continuous chain from a single metal rod or wire can be effected by the operation of the machine alone.

To enable others skilled in the art to make and use my invention, I will proceed to describe it.

A represents the frame or platform to which the mechanism is secured. Near the top of the machine, in proper bearings, is mounted the main shaft B, upon which are secured three double cam-wheels a, b, and c, by which the movements of the dies and other parts cutting, forming, and joining the links are controlled, as will be hereinafter explained. On the end of shaft B is a gear-wheel, j, which imparts motion to shaft D, and from thence by means of the bevel-gear to wheel F on shaft E. The periphery of wheel F is provided with a groove, extending part way around it. A portion of the periphery equal in length to the rod a*, Fig. 6, which is to form one link, has no groove, or but a very slight one. Directly underneath wheel F, and revolving in the same vertical plane, is a duplicate wheel, F'. (See Fig. 2 of the drawings.) The end of the wire or rod forming the chain is entered between these two wheels, and as they revolve the rod is caught between those portions having but a slight groove, and fed forward through a hole in the side of the frame C for a distance equal to rod a*, at which point the

further feeding in of the rod ceases by virtue of the wheels having revolved to such a position that their grooved portions come opposite the rod and their hold thereon released. At this time the cam c comes in contact with lever e, the lower end of which, engaging with the chisel e, Fig. 5, moves the latter forward and cuts off the wire a* for the first link. Immediately thereafter the projection 1 of cam a operates the lever a', which moves the sliding die f forward, by which the wire is forced against a corresponding die, f', Fig. 4; which is forced down into proper position at the required time by cam b, by which operation the rod is bent, as shown by b*, Fig. 6. Immediately after this process the cam b, striking lever b', shoves forward the plunger g g, the hinged arms h h of which, coming in contact with the rod b* on each side of the point, where it is firmly held between f and f', carries the ends of b* forward, and at the same time inward toward each other, the latter movement being imparted by the converging movements of arms h h impinging against the curved sides of the frame, as shown in Fig. 5, by which operation the rod is bent in the form shown by c*, Fig. 6. At this stage the cam a, striking the sliding frame k, Figs. 2 and 3, moving it forward, causing its rear portion, k', to enter a beveled recess in the upper portion of f', raising it, and thus releasing the link c*, which is then shoved bodily forward by a further movement of the die f, leaving it deposited with its ends in the recesses r r over the opening s, as indicated by blue lines in Fig. 5, the ends of c* in coming to this position being thrust through the bent portion of the preceding link, which is held upright in the opening s for that purpose by a spring-latch, s', working in the lower portion of said opening s. A plunger, x, is then forced down by the point 2 of cam a, which plunger striking the preceding link d*, which, resting upon the arms of the unfinished link c*, as shown in red in Fig. 6, forces the end of the latter with d* down into the opening s, by which the ends of c* are bent and clasped around the upper portion of link d*, the link c* being at the same time raised to a vertical position and carried down far enough to occupy the position from which d* had been forced in the operation. As the cam a revolves, a projection, 3, upon its side engages under pin o of the arm x',

which, being attached to plunger x , raises the latter up out of the way of the succeeding link and into a position for repeating its operation, as above described. The point 2 of cam a , as it continues to revolve, next strikes the pivoted lever a^2 at the opposite side of the machine, causing it to operate the plunger i , Fig. 5, the two projecting joints i' i' of which are thus forced against the bent ends of the link standing upright in opening s , by which the bent portion of the link is changed from the form shown at e^* to that of f^* , Fig. 6, thus completing the process of forming and attaching a link. The process thus described is repeated twice at each revolution of the shaft B , the cams thereon being duplicated or double, as already stated, and as shown in Fig. 2. Thus the process or operation is made continuous by the continued revolution of the shaft B , whereby link after link is formed

and added to the chain so long as the wire of which it is made is furnished to the machine. By this improved method of constructing and operating my machine I obtain one that is simple, compact, and that performs its work in a most efficient, rapid, and satisfactory manner, and by which the labor and cost of producing the chain is greatly lessened.

Having thus described my invention and its operation, what I claim is—

Constructing a chain of the form herein represented from a single rod or wire by one continued process, by means of an automatic machine constructed, arranged, and having all its parts operated substantially as described.

L. KING.
